UNITED STATES PATENT OFFICE.

CHARLES P. MADSEN, OF SALT LAKE CITY, UTAH, ASSIGNOR, BY DIRECT AND MESNE ASSIGNMENTS, TO PELOUZE MANUFACTURING COMPANY, OF CHICAGO, ILLINOIS, A CORPORATION OF ILLINOIS.

SAD-IRON.

1,034,129.

Specification of Letters Patent. Patented July 30, 1912.

Application filed January 22, 1908. Serial No. 412,176.

To all whom it may concern:

Be it known that I, CHARLES P. MADSEN, citizen of the United States, residing at Salt Lake City, in the county of Salt Lake and State of Utah, have invented a new and useful Sad-Iron, of which the following is a specification.

The invention relates more particularly to electrically heated sad irons, and among 10 the important objects of said invention the following may be noted: First, to provide a sad iron in which practically all the heat will be applied or confined to the bottom where it is needed, and loss by convection 15 and radiation through other parts of the structure will be practically eliminated, thereby securing an iron which heats quickly, one that is very convenient to operate and one which is economical in the amount of 20 electrical energy absorbed or used. Second, to provide a structure in which all of the parts are so constructed, interfitted and related that they can be assembled for use and disassembled for renewal or repair by an 25 unskilled person, without destroying or disturbing the close adjustment or relation of said parts; in which the interchanging of new for damaged parts and the expense 30 thereof is confined to the damaged part; and to provide a unitary, self-contained and 35 complete heater readily separable from and mountable in the iron by an unskilled person without the necessity of tinkering with electrical connections. Third, to provide 40 novel and effective means for insuring the proper heating of the different portions of the bottom of the iron. Fourth, to provide a novel structure that will obviate the necessity of placing the iron on a stand when 45 not in use, thereby avoiding lifting the same. Fifth, to provide a combined plug and switch of novel construction, so associated with the other features that the operator can easily graduate the heat to the desired degree without stopping the ironing 50 operation or detaching the plug from and attaching it to the iron.

The preferred embodiment of the invention is illustrated in the accompanying drawings, wherein:

Figure 1 is a side elevation of the sad iron; Fig. 2 is a vertical longitudinal sec-

tional view therethrough; Fig. 3 is a cross sectional view substantially on the line 3—3 of Fig. 2; Fig. 4 is a cross sectional view on the line 4—4 of Fig. 2; Fig. 5 is a detail perspective view of the heater unit or element. Fig. 6 is a bottom plan view of the same; Fig. 7 is a horizontal sectional view through the combined switch and plug; Fig. 8 is a detail perspective view of the holding clip for the combined switch and plug; Fig. 9 is a bottom plan view of a slightly modified form of heater element.

Similar reference numerals designate corresponding parts in all the figures of the drawings.

In the embodiment illustrated, the bottom element or ironing plate 10 is flat and rimless. It has the usual triangular form and I make it comparatively thin for several purposes, namely, to reduce the mass to be heated to a minimum, that the iron may be quickly raised to a working temperature and for the further purpose of enabling me to place the electric heater or source of heat as close as practicable to the ironing surface. It has an upstanding central enlargement, platform or projection 11, preferably triangular in form, and from which rises a single bolt or post 12. This bolt may be either integral with the bottom element or the head may be embedded therein as desired. The unitary heater unit or element 13 is located or placed upon the bottom plate and comprises a plate or body 14 of asbestos or other suitable insulating material which is also a non-conductor of heat. The under side of this body has a substantially triangularly shaped socket, recess or opening 15 that receives, substantially fits and interlocks with the enlargement 11 of the bottom plate and the plate and heater unit are thus locked against relative displacement or rotary movement 95 although they are perfectly free to be separated when the heater or other parts are to be renewed, as clearly shown. The fastening or clamping bolt 12 extends upward through the heater unit and receives a nut 100 29 as hereinafter described.

The heater unit preferably comprises the insulating body 14 in the bottom or under-side of which is permanently embedded a

ribbon, wire or other strand 18 of electric resistance material that is formed into convolutions laid or wound in a thin single plane or layer around the socket 15, the 5 turns thereof reaching substantially the point and the sides of the iron, as shown in Fig. 6. The convolutions, however, may be extended completely around the socket, as shown in Fig. 9, wherein the strand of resistance material is designated 18^a. The several turns of the conductor are separated by a ribbon or strip of asbestos or other suitable insulating substance 19 which may be wound with the ribbon. The exposed edges 10 of the resistance wire 18 are thus substantially flush with the bottom of the heating unit and the unit is therefore adapted to present a substantially smooth, flat under surface arranged for substantially perfect 15 contact with the upper surface of the bottom plate. By this construction the heat is most easily transmitted directly to the bottom plate with a minimum loss and with a maximum efficiency. To prevent the flow 20 of electricity from the heater coil to the metallic bottom plate I interpose a thin sheet of mica 52 between these members which prevents the exposed edges of the winding from contact with the bottom plate, 25 but does not prevent the flow of heat to any appreciable extent. The mica sheet has a triangular opening to receive the enlargement 11. The lower side of the heater element 13 is provided with a transverse recess 30 23 somewhat deeper than and located adjacent to the rear end of the recess or socket 15. The ends of the resistance wire or ribbon 18 are carried through the body of the heater unit into this recess for connection 35 with suitable terminals described herein- 40 after.

The top or weight element 24 is superimposed upon the heater element and its underside is provided with a large cavity or 45 recess 25 which forms a depending rim or edge 24' and provides a peripheral shoulder 24'' extending entirely around the iron. The lower part of the heater element is provided with a shoulder which is adapted to 50 receive the shoulder 24'' and the heater element consequently closes said cavity and supports the body or upper part in position. The upper part 14 of the heater element is conformed to and fills the cavity and 55 as the rim 24' is peripheral and conforms to the shape of the iron the cavity is triangular in shape and consequently the heater element and body portion, when clamped together, are rotatably interlocked and mutually hold each other against displacement 60 both laterally and rotatively. For the accommodation of the bolt 12 and nut 29 the top member 24 is provided with a recess 28 in its upper side and with a vertical hole or 65 opening 26 which connects the recess 28

with the cavity 25. I make this hole 26 larger in diameter than the shank of the bolt to eliminate metallic contact between the two parts and thus prevent the heat which is conveyed up through the bolt 12 70 from passing directly into the top plate. I preferably pack some heat insulating substance 27 loosely in the space surrounding the bolt to further insulate the bolt from the top member. The recess 28 accommodates the nut 29 and the nut is thus sunk below the upper surface of the iron out of the way of the fingers of the operator. To further protect the body from conveyed heat, I interpose a heat insulating washer 80 31 below the nut and I protect this washer by a metallic washer 30 interposed between the nut 29 and the washer 31. The three main parts of my iron are held firmly together in interlocked condition by this single clamping member or bolt 12 and when the nut 29 is removed these three interlocked parts are freely separable from each other.

In my novel structure I provide a handle 90 which performs the dual function of an operating handle and a support for the iron. This comprises a standard 34 suitably secured by its stem 35 to the forward end only of the iron. The shank carries at its 95 upper end a horizontally disposed rod 36 upon which is a grip 37. This handle, being supported only upon the front end of the iron, leaves the rear portion of the iron clear of obstruction for the plug switch. The grip 37 extends beyond the rear end of the iron and in conjunction with lugs 38, which project from the rear end of the body 24, supports the iron on its rear end when it is not in use. It is therefore only necessary 100 to tip the iron on end instead of lifting it whenever it is not in active use for a moment. The projecting lugs are preferably formed integrally with the top member and their edges 39 lie in the plane of the free 105 end of the handle. The heater element 13 is provided with terminals 20, which are thin metallic strips arranged in parallel vertical position with their lower ends projecting downward into the recess 23 and to which the 110 ends of the heating coil 18 are suitably attached. These terminals extend upwardly above the upper face of the heater unit and into a longitudinal recess, guideway or groove 33 provided in the rear part of the 115 upper face of the body 24 and directly beneath the overhanging handle 37. These terminals 20 are held firmly in relative position by being embedded in an upstanding 120 column or block 21 of insulating material which in turn is held in a suitable opening provided in the heater element 14. The top member 24 is provided with a suitable opening 32 through which the block 21 is inserted when the parts of the iron are as 125 130

sembled. The upper ends 22 of the terminals project above the upper end of the block 21 into the guideway 33 and form contact blades in position to be connected with a switch plug to be described and by which the supply of electricity to the iron is controlled. The guideway 33 extends forwardly from the rear end of the iron to the recess 28. Its side walls form a suitable longitudinal guide for the switch plug which comprises a block or casing 40 of insulating material having an upstanding operating knob 41 at its front end which is at all times, while the switch is in the guideway, within convenient reach of the fingers of the operator. The block is provided with a pair of parallel horizontal longitudinal bores 42 in which are located sleeves 43 terminating at their front ends in fingers 44 that are arranged to engage the upper ends 22 of the contact blades of the heater. The rear ends of the sleeves 43 constitute receiving sockets for the terminals of the current conductors 45. These conductors preferably enter the plug through an upstanding loop ear 46 on the plug and are fastened in the contact sleeves by screws 47 which also serve to hold the sleeves in place, as is clearly shown in Fig. 7. The switch plug is slideable in its guideway so that the current may be shut off or turned on at the will of the operator. However, it obviously may be pulled right out of its socket when the iron is to be put away. In order that the plug may be held in its several positions and at the same time left free to be entirely disconnected from the iron, I provide a metallic spring clip 48 having fingers 49 which straddle or embrace the knob 41 and terminate at their free ends in V-shaped portions 50. These ends engage in either of two sets of notches 51 in the top of the switch plug and yieldingly hold the switch in either of its two positions. The clip is held in position by being clamped under the washer and thumb-nut 29. It is to be noted that the knob 41, by which the switch plug can be easily moved from one position to the other is always positioned directly below the handle 37 and in convenient position for the operator to turn the current on or off without removing the hand from the handle.

It will now be clear that my novel sad iron structure possesses many advantages.

Each of the elements may be manufactured separately and may be individually interchanged for new parts at little expense and without the necessity of destroying the entire iron or returning it to the factory for repair. In fact one of the important purposes of my invention is to provide an iron which is fool-proof, simple and capable of manipulation or of being readily assembled or disassembled by an unskilled

person without destroying its parts or their adjustment. The several elements which constitute the complete structure are superimposed one above the other and clamped in their non-rotative engagement by a single clamping device, which in this case comprises the central bolt and nut. The plug switch conveniently enables the operator to make and break the circuit and thereby control the temperature to a nicety without stopping the ironing operation or removing the hand from the iron.

A further advantage is that the heater unit completely isolates or separates the bottom element from the top element and there is practically no loss of heat to the top member by convection or radiation for the reason that the comparatively great body of heat insulating material above the coils prevents the passage of heat to the top element. Furthermore, practically no portion of the thin bottom element is exposed to the air. The only part that might convey heat to the top element is the single bolt 12 but as shown, this bolt is completely insulated from the top element.

Experience has demonstrated that the forward or "point" portion of the smoothing surface should be the hottest and also the side or edges thereof, while the coolest portion should be the center to prevent scorching. By distributing the heating winding as shown in Figs. 6 and 9, these results can be readily and satisfactorily obtained without the necessity of cumbersome coils.

As the electric heating unit gives out after a longer or shorter use, it has to be replaced and my novel structure provides for the accomplishment of this necessary repair with the outlay of a minimum of time, labor and expense. When it is desired to renew the heating unit, it is simply necessary to loosen the single fastening device, disassemble the parts, place the new heater and other parts together and clamp them, no careful readjustment is necessary. These heater units can therefore be made as separate articles of manufacture. In addition, it is now customary to make irons of the same weight, but of different temperatures for different purposes, and a person can purchase extra elements of different temperature capacities and place them in position himself, thus doing away with the necessity of buying extra complete irons.

A further advantage of my novel iron resides in the ease with which the operator controls the temperature of the iron. Heretofore it has been customary to provide irons with heating means adapted for the highest temperature required. Consequently when light work was being done great care was necessary to prevent scorching. By the use of my easily operable switch the operator using my iron has the temperature un-

der constant and convenient control. When the iron becomes too hot he turns the current off and when it falls below the required temperature turns it on again and all without removing the hand or stopping operation. This easy control results in the use of a minimum quantity of electric current. The lugs 38 are long enough to protect the switch when it is withdrawn a sufficient distance to break the electric circuit, so that when the iron is turned on end the weight of the iron will not accidentally return the switch to its connecting position.

As many modifications of my invention will doubtless suggest themselves to those skilled in the art, I do not limit or confine my invention to the specific structure herein shown and described.

The circuit closing and breaking device or mechanism disclosed herein forms the subject-matter of and is claimed in my pending divisional application, Serial No. 608,051, and is not specifically claimed herein.

Having thus fully described my invention, what I claim as new, and desire to secure by Letters Patent, is:

1. The improvements herein described comprising a metallic body portion containing a cavity, a unitary heater element interlocked with said body portion and closing the cavity therein, said heater element comprising a plate of refractory insulating material, and a single plane resistance winding embedded on one side of said plate with its edges exposed, a heat receiving and transmitting plate interlocked with said heater element, and a central clamping post extending from the hot plate through said element and body portion and secured upon the latter.

2. The improvements herein described, comprising a body portion, in combination with an electric heater element composed of a plate of refractory insulating material, a single layer resistance winding on one side thereof, a column of insulating material extending from the plate, and contact blades arranged in said column and with which the ends of said resistance winding are connected, a switch member having complementary contacts movable into and out of engagement with said blades, a plate to be heated, and means for clamping said heater element between said plate to be heated and said body.

3. In an electric sad iron, the combination with a bottom element, of a self-contained heater unit located thereon and having a portion that has a non-rotative but freely detachable interlocking engagement with said bottom element to prevent the relative rotation of said heater unit and bottom element, and a single clamping device for securing said elements together and maintaining said

portion and the bottom element in interlocked, non-rotative engagement.

4. In an electric heater, the combination with a bottom element having an upstanding triangular platform, of a separate heater holding element mounted on the bottom element and comprising a body having a triangular socket that receives the upstanding platform, resistance wire embedded in said body and arranged in convolutions about the socket therein, and means for clamping said heater holding element upon said bottom element.

5. In an electric heater, the combination of a flat rimless bottom element provided with a central upstanding interlocking projection on its upper side, a thin layer of insulating material placed on the upper side of the bottom element and having an opening to receive said projection, and a heater holding element detachably and non-rotatably interlocked with said bottom element by said projection thereon, and a layer of heating conductor permanently cemented upon the lower side of said heater holding element and separated from the bottom element by said layer of insulating material.

6. In an electric heater, the combination with a bottom element, of a heater holding element associated therewith and including a body that is a poor conductor of heat, a top element, said heater holding element and top element being provided one with a cavity, the other with shouldered edges that detachably engage in the cavity, a bolt and a nut for detachably securing the elements together, and insulating means separating the bolt and nut from the top element.

7. In an electric heater, the combination with a bottom element, of a heater holding element thereon, a top element supported solely upon the heater element and having a recessed underside in which the upper portion of the heater holding element is engaged, said heater holding element separating the top and bottom elements and maintaining them out of contact, and a single insulated bolt nut clamping device extending from said bottom element through said heater element and top element.

8. In an electric heater, the combination with a bottom element having an upstanding angular portion, of a heater holding element located thereon and having an opening that receives said upstanding portion, a top element resting on and entirely separated and insulated from said bottom element by said heater holding element, and having a recessed underside that receives the upper portion of the heater holding element, and means for fastening the elements together.

9. In an electric heater, the combination with a bottom element having a central upstanding angular portion, of a heater hold-

ing element comprising a body of insulating material having an interlocking portion that receives the angular portion, and resistance material located in the body, an upstanding bolt carried by the angular portion and extending through the heater holding element, a top element provided with a recessed underside that receives the upper portion of the heater holding element body, 10 and said top having an opening of greater diameter than the bolt and receiving the bolt, a clamping nut on the upper end of the bolt, and heat insulating material interposed between the nut and the top element.

15 10. In an electric heater, the combination with a bottom element, of a top element having a socket, a heater holding element of non-heat-conducting material interposed between the top and bottom elements, a post 20 composed of insulating material carried by the heater element and located in the socket of the top element, and resistance material arranged in the heater holding element and having spaced terminals located in the post.

25 11. In an electric heater, the combination with a flat rimless bottom element having a central upstanding enlargement, and a bolt projecting upwardly from the enlargement, of a heater holding body of insulating material located on the bottom element and having an interlocking opening that receives the enlargement and through which the bolt passes, said body being provided with an upstanding post, electrical resistance located 30 in the lower portion of the body and having terminals extending upwardly through the post, a top element located on the heater holding body and having its underside recessed and receiving the same, said top element having an opening of greater diameter than the bolt and receiving the same, said top element also having a socket through which the post passes, a clamping nut threaded on the upper portion of the bolt, a 35 heat insulating washer interposed between the nut and top element, and electrical connections with the terminals in the post.

40 12. In an electric heater, the combination with a bottom element and a heater holding element detachably located thereon, of a top element having a recess in its upper side, and a perforation entering the bottom of the recess, a bolt carried by the bottom element and detachably passing through the 45 heater holding element and the perforation into the recess, and a clamping nut threaded on the upper end of the bolt and located in the recess.

50 13. In an electric heater, the combination with a bottom element and a heater holding element of non-heat-conducting material associated therewith, of a top element located upon the heater element and having a recess in its upper side and a vertical bolt hole entering the bottom of the recess, a securing

bolt for the elements passing through the bolt hole into the recess, a washer of insulating material located in the recess, upon the bolt, and a nut threaded on the bolt and bearing upon the washer.

70 14. In an electric sad iron the combination of a comparatively thin member to be heated, a self-contained heating device separable as a unit from but intimately associated with said member to be heated and having a non-rotative interlocking engagement therewith, a comparatively thick and heavy top member non-rotatively, but separably interlocked with said heating device, and a single clamping means for holding 80 said members in an assembled structure.

75 15. The improvements herein described, comprising a body portion having switch block guides, in combination with an electric heater element, comprising a plate of refractory insulating material containing a resistance winding and having contact members which extend through said body adjacent to said guides, a sole plate to be heated, means clamping said body and sole plate 85 upon said element, and a switch block movable in said guides normally covering said contact members and containing contacts for engagement with said members.

90 16. The improvement herein described, comprising a body portion, in combination with an electric heater element, comprising a plate of refractory insulating material containing a resistance winding and having contact members which extend through the 95 top of said body, a plate to be heated, means clamping said body and plate upon said element, and a switch block movable on said body normally covering said contact members and containing contacts for engagement with said members.

100 17. In an electric sad iron, a body portion containing a cavity in its lower side and a hole extending vertically therefrom, in combination with a heater element comprising 105 a plate carrying a resistance winding and closing said cavity, a column of insulating material extending from said plate through said hole, contact blades in said column and forming the terminals of said winding, a 110 bottom plate to be heated, means clamping said heater element between said plate and body, and a switch block movable on said body and containing contacts for engagement with said blades.

115 18. In an electric sad iron, a body portion containing a bottom cavity and a hole extending up through the body from the cavity, in combination with a heater comprising 120 a plate carrying resistance winding and closing said cavity, a column of insulating material extending from said plate through said hole, contact blades in said column and forming the terminals of said winding, a 125 bottom plate, means clamping said heater 130

element between said bottom plate and body, a switch block movable on said body, and containing contacts for engagement with said blades.

5 19. In an electric sad iron, a body portion containing a recess, in combination with a unitary, removable heater element in interlocked, but readily separable, engagement with said body and composed of a refractory insulating plate, contact members, and a single layer ribbon winding whereof said members form the terminals, a plate to be heated interlocked with said element, and means clamping said element between said plate and said body.

10 20. In an electric sad iron, the combination with a bottom element, of a top element, a unitary heater holding element clamped between the top and bottom elements and easily separable therefrom, said heater holding element having electrical resistance material therein, and a combined switch and plug separate from the top and bottom elements and detachably associated 25 with the heater holding element for connecting electrical leads to and disconnecting them from the resistance material.

15 21. An electric sad iron comprising a body portion having a recess in its underside, in combination with a substantially triangular plate of refractory insulating material suitably interlocked with the lower edge of said body, a single layer resistance winding upon the lower side of said plate, 30 contact members connected therewith and rising from the top of said plate, a bottom plate suitably interlocked with said refractory plate, means clamping said body and said bottom plate upon the refractory plate, 35 and a contact block or plug having contacts and movable into and out of engagement with the said contact members, substantially as described.

40 22. An electric sad iron comprising a body portion having a recess in its underside, in combination with a substantially triangular flat plate of refractory insulating material suitably interlocked with the lower edge of said body, a single layer resistance winding upon the lower side of said plate, 45 contact members connected therewith and fixed upon the top of said plate and extending through the top of said body, a bottom plate suitably interlocked with said refractory plate, a post extending from the bottom plate through said refractory plate and body, a nut thereon for clamping said body and said bottom plate upon the refractory plate, and a contact block or plug movable 50 upon the body and having contacts for engagement with the said contact members.

55 23. In an electric heater the combination with a flat, rimless bottom element provided with an elongated central upstanding enlargement, of a flat sheet of insulating ma-

terial located on the upper side of the element and surrounding said enlargement, and a freely removable heater element resting upon said upper side of the bottom element and fitting said enlargement, comprising an 70 insulated body having a volute winding of resistance ribbon permanently cemented upon its lower side and separated from the bottom element by the flat insulating sheet.

75 24. In an electric sad iron, the combination with a bottom element, of a heater holding element associated therewith and including a body that is a poor conductor of heat, a top element, said heater holding and top elements being provided one with an opening, the other with a portion that detachably engages in the opening, a single bolt upstanding from said bottom element and passing through said heater holding element and top element, a nut on said bolt for detachably securing all the elements together, and heat insulating means separating the bolt and nut from the top element, substantially as described.

80 25. In an electric sad iron the combination with a bottom element, of an independent, readily separable heater unit resting thereon and containing a heating conductor in heating relation to said bottom element, and a top element resting on and completely separated from said bottom element by said heater unit, said top element having a recessed underside in which the upper portion of the heater unit is engaged.

85 26. In an electric sad iron, the combination with a bottom element, of a detachable heater unit thereon, a top element supported solely upon the heater unit and having rim edges with which the upper portion of the heater element separably interlocks, said 100 heater element separating and insulating top and bottom elements, a bolt connecting the top and bottom elements and insulated from and passing through the heater unit, and said elements and heater 110 unit being serially interlocked against relative rotation, substantially as described.

90 27. In an electric sad iron, the combination with a bottom element, of a heater holding element, one of said elements having an 115 interlocking socket, the other having an interlocking enlargement located in the socket, a top element resting on the heater holding element, one of the latter elements being provided with an opening, the other having an interlocking portion engaged therein, and a single central fastening device for firmly binding the several elements together.

95 28. In an electric sad iron the combination with a sad iron body, of spaced integral 120 projections extending from the rear end of the same, and a handle grip having a connection solely with the front end of the body, said grip extending beyond the rear end of said body and adapted in conjunc- 125 130

tion with said projections to support the sad iron on end, and independent electric connections for said iron.

29. In an electric sad iron, an upper weight member and a light bottom smoothing plate conformed horizontally in size and shape therewith, in combination with a unit heating element of equal horizontal dimensions with said top and bottom members interposed therebetween thermically isolating one from the other and adapted to deliver heat to the bottom plate, and a single device clamping said parts together.

30. A composite electric sad iron body composed of a relatively heavy metallic upper member, a bottom metallic smoothing plate and an interposed body of heat insulating material, said three members being identical in shape and size at their horizontal meeting surfaces, a single fastening device binding the members together, and a heating winding permanently carried by said insulating body in heating relation to said bottom plate only.

31. An electric sad iron comprising a thin, flat metallic bottom plate, a unitary heater removably mounted thereon and interlocked therewith against rotary displacement, an upper body member removably mounted upon but rotatively interlocked with said heater, said bottom plate, heater and upper member conforming to each other in size and shape at their meeting surfaces, and a single device for clamping said parts together.

32. In an electric sad iron, a body consisting of three distinct parts, namely: a heavy metallic top member a metallic bottom member, which is both thin and light, and an intermediate member of both heat and electricity insulating material, and means clamping said members firmly but separably together said members being conformed in size and shape to each other at their meeting

surfaces whereby said top and bottom members are thermically isolated from each other when the parts are in operative relation.

33. In an electric sad iron a substantially triangular, thin bottom plate, a similarly shaped self-contained heater unit removably superposed thereon and an interlock for preventing relative displacement thereof, in combination with a heavy substantially triangular weight member removably superposed on said heater, said bottom plate, heater unit and weight member being of substantially identical shape and size horizontally whereby the upper and lower members are completely isolated from each other against heat radiation by said heater, and a single clamping device for fastening said parts together.

34. In an electric sad iron a substantially triangular, thin bottom plate, a similarly shaped self-contained heater unit removably superposed thereon and substantially completely covering the upper surface thereof, and an interlock for preventing relative displacement thereof, in combination with a heavy, substantially triangular weight member removably superposed on said heater substantially completely covering the upper surface thereof and completely isolated against heat radiation from said bottom member by said heater, an interlock for preventing rotation between said upper member and said heater, and a single clamping device for fastening said parts in interlocked relation.

In testimony, that I claim the foregoing as my own, I have hereto affixed my signature in the presence of two witnesses.

CHARLES P. MADSEN.
